RELAY

Joseph C. Tamsitt, Aurora, Ill., assignor to
 Richards - Wilcox Manufacturing Company,
 Aurora, Ill., a corporation of Illinois

Application May 21, 1931. Serial No. 539,001

8 Claims. (Cl. 200—98)

The present invention relates to relays or switching devices, and embodies improvements in the general type of relay wherein the energization of a contact closing coil actuates an armature to cause a movable contact to engage with a cooperating contact, and wherein the energization of a contact opening coil actuates said armature to enable the movable contact to separate from said cooperating contact. The present construction of relay has been devised particularly for use with elevator signal and control apparatus, such as I have disclosed in my copending application, Serial No. 555,909, filed August 8, 1931, and certain features of this relay construction have been developed to meet conditions and requirements encountered in elevator signaling work.

One of the objects of the invention is to resiliently lock the armature and movable contacts against vibration when said armature and contacts are in either their circuit opening or circuit closing positions. This vibration tends to arise owing to the fact that alternating current is generally used to energize the coils, and owing to the fact that with the armature and movable contacts in their circuit opening position the coil which has caused movement of these parts to that position is successively energized with the movement of the elevator car past each floor level. In the preferred embodiment of the present invention this vibration is avoided by a unique coaction between the movable contact spring and the armature whereby the contact spring locks the armature in its attracted position and holds it resiliently pressed against the coil or electromagnet.

Another object of the invention is to provide a very simple, reliable and inexpensive relay of the general type referred to above, wherein no pivot mountings are necessary for the contacts and no pigtails or other flexible electrical connections are necessary in establishing circuit connections with the contacts.

Another object is to provide a relay of the above description wherein the electromagnet, the armature and the contacts each have unit removability from a supporting panel whereby any one of the parts can be removed and replaced on the panel without disturbing any of the other parts.

Other objects and advantages of the invention will appear from the following detail description of a preferred embodiment thereof. In the accompanying drawing illustrating such embodiment:

Figure 1 is a front elevational view of the relay showing the parts in contact closing position;

Figure 2 is a fragmentary elevational view showing the parts in contact opening position, 60 and

Figure 3 is a transverse sectional view through the supporting panel, illustrating the unit removability of the parts on this panel.

The parts are mounted on a back panel 5 composed of insulation. These parts include two duplicate electromagnets 6 and 6a each comprising a soft iron core and a coil wound thereon. The ends of the cores are indicated at 7 and 7a. Each electromagnet is separately mounted on the back panel 5 through an L-shaped bracket 8 having its horizontal leg secured to the electromagnet core by a screw 9. The vertical leg of the bracket is secured to the back panel by two bolts 11 spaced to each side 75 of the medial line of the electromagnet and passing through the bracket leg and back panel. Conductors 12 and 13 lead from each electromagnet and connect with terminal posts 14 and 15, respectively, which extend through the supporting panel and are adapted to have circuit connections established therewith on the rear side of the panel. Corresponding parts of the right hand electromagnet 6a are indicated by the same reference numerals with the suffix a. 80

The armature is a T-shaped rocking unit comprising the two side arm portions 18, 18a and the depending leg portion 19. The cross bar making up the side arm portions is of magnetic material, such as soft iron, and is drilled 90 intermediate its ends for a pivot screw 21 which extends through the back panel 5. A spacer sleeve 22 is mounted on said pivot screw between the armature and the panel, as shown in Figure 3. Secured in the ends of the arms 18, 18a are brass plugs 23, 23a which are adapted to strike and bear against the core ends 7 and 7a of the electromagnets. In the illustrated construction, the downwardly extending leg 19 consists of a plate having its upper end set into a 100 notch in the cross bar portion, and secured therein by welding or soldering. The lower end of said leg 19 is tapered to form a comparatively narrow contacting edge 19'.

The movable contact of the relay is indicated at 25 and the cooperating contact at 26. The contact 25 is secured to the underside of a leaf spring 27, and the contact 26 is secured to the upper side of a leaf spring 28. Said springs are mounted in supporting posts 29 and 30 110

which project from the front side of the panel 5, the inner ends of these posts having threaded extensions 31 passing through the panel and receiving nuts on the back side thereof. The 5 electrical connections with the contacts 25 and 26 are established through these posts and threaded ends 31. The outer ends of said posts are slotted longitudinally, as indicated at 32, to form clamping halves for securing the springs 10 27 and 28. Screws 33 pass through the split ends of the posts and rigidly clamp the ends of the springs in said slots. The ends of the springs have longitudinally extending slots therein through which the screws 33 pass. 15 These slots permit the springs 27 and 28 to be shifted longitudinally to secure proper registry between the contacts 25 and 26 and also to properly relate the cam surfaces in the spring 20 27 with respect to the lower leg 19 of the armature. It is also possible to move the springs and contacts upwardly or downwardly in securing the proper adjustment of the parts by loosening the nuts on the threaded ends 31 of the mounting posts and rotating the posts 25 slightly.

The contact spring 27 is formed with a cam surface 36 which slopes upwardly from the outer portion of the spring up to the higher inner portion which carries the contact 25. In this 30 higher inner portion, just beyond the cam slope 36, the spring is also formed with a notch-like depression 37. When the left hand electromagnet 6 is energized to close the contacts 25, 26 the armature leg 19 is caused to slide across the cam 35 surface 36, thereby camming the spring 27 downwardly and forcing the contact 25 into engagement with the contact 26. At the end of its swinging movement the armature leg 19 snaps into the depression 37. The parts are so 40 proportioned that at this time the spring 27 is exerting a pressure against the leg 19 upwardly and to the left. This holds the cross arm 18 of the armature resiliently pressed against the stop 7 on the electromagnet 6. Such 45 occurs instantly with the energization of the magnet 6, and thereafter the parts are locked against vibration with the contacts 25 and 26 held in engagement and with the cross arm 18 held against the electromagnet. Hence, the 50 pulsations of the alternating current, or successive energizations of the magnet 6, do not tend to vibrate any of the parts.

When the right hand magnet 6a is energized the armature is rocked in the other direction, causing the leg 19 to snap out of the depression 37 and permitting the contact 25 to separate from the contact 26. As shown in Figure 2, the cam slope 36 then presses upwardly against the left hand edge of the leg 19, the parts being so proportioned that this spring pressure resiliently holds the cross arm 18a pressed up against the stop 7a on said magnet. Hence, even though this magnet 6a is energized as the elevator car passes each floor level, and 65 such energization is effected by alternating current, the armature is resiliently locked against vibration and cannot vibrate the contact spring 27.

The resilient locking of the armature and the 70 movable contact in both the open circuit and closed circuit positions of the device avoids the possibility of any unreliable or accidental operation of the contacts, minimizes wear of the parts, and avoids noise. In mounting, adjusting or 75 replacing parts, it will be noted that the elec-

tromagnets 6, 6a, the armature 18-19 and the two contact springs 27 and 28 are each capable of separate removal from the back panel 5 without disturbing any of the other parts.

Having thus described my invention what I 80 claim as new and desire to secure by Letters Patent is:

1. In a relay of the class described, the combination of a pair of electromagnets, a T-shaped armature pivotally mounted for rocking movement and comprising two cross arms and an angularly extending leg, each of said cross arms being adapted to be attracted by one of said magnets, a pair of contacts, a leaf spring supporting one of said contacts at its free end, said armature leg being adapted to swing substantially parallel to and along said leaf spring, and means on said leaf spring engaged by said armature leg for resiliently locking said armature in both of its attracted positions. 95

2. In a relay of the class described, the combination of a supporting panel, a pair of electromagnet units, a T-shaped armature unit comprising two cross arms and an angularly extending leg, each of said cross arms being 100 adapted to be attracted by one of said magnets, a relatively stationary contact unit, a movable spring contact unit adapted to cooperate therewith, contacts carried at the free ends of said units, means on said spring unit adapted to be 105 engaged by said armature leg for causing relative movement between said contacts, said movable spring unit resiliently locking said armature leg in each of its attracted positions, and means separately mounting each of said units 110 on said supporting panel whereby any one of said units can be separately removed and replaced without disturbing any of the other units.

3. In a relay of the class described, the combination of a pair of electromagnets, an armature pivotally mounted between said electromagnets and rockable to attracted position by each of said magnets, a pair of contact springs provided with contacts at their free ends normally 120 disengaged, and means on one of said contact springs engaged by an extending portion of said armature for forcing said spring outwardly to cause engagement of said contacts, said means serving to hold said armature resiliently in 125 both of its attracted positions.

4. In a relay of the class described, the combination of a pair of electromagnets, an armature pivotally mounted between said electromagnets and rockable to attracted positions by 130 each of said magnets, a pair of contact springs provided with contacts at their free ends normally disengaged, means for varying the positions of said contact springs, and means on one of said contact springs engaged by an extending portion of said armature for forcing said spring outwardly to cause engagement of 135 said contacts, said means serving to hold said armature resiliently in both of its attracted positions.

5. In a relay of the class described, the combination of a pair of electromagnets, a pivotally mounted armature extending across said electromagnets and adapted to be rocked about its pivot by attraction of each of said magnets, a 145 first contact spring, a contact carried at the free end thereof, a second contact spring, a contact carried at the free end thereof, and a cam surface formed on said second spring and continuously engaged by said armature for caus- 150

ing said contacts to engage, said surface serving to hold said armature resiliently in both of its attracted positions.

6. In a relay of the class described, the combination of a pair of electromagnets, an armature rockable into attracted position by each of said magnets, a pair of laterally extending contact springs supported at their opposite ends and having their adjacent ends overlapping, contacts carried by the free ends of said springs and normally spaced apart, and a cam surface on one of said springs continuously engaged by said armature for causing engagement and disengagement of said contacts upon attraction of said armature by said magnets, said cam surface comprising an integrally formed offset sloping portion having a notch formed at one end thereof.

7. In a relay, a pair of electromagnets, a pivotally mounted armature rockable to attracted position by each of said magnets, a pair of contact springs provided with contacts at their free ends normally disengaged, and cam means on one of said contact springs continuously en-

25

gaged by an extending portion of said armature and adapted to effect engagement and disengagement of said contacts upon respective attraction of said armature by said magnets, said cam means preventing release of said armature from either of its attracted positions except by attraction of said magnets.

8. In a relay, a base member, a pair of separately mounted electromagnet units mounted on said base member, a pivotally mounted armature rockable into attracted position by each of said magnet units, a pair of separately mounted contact spring units on said base member having contacts at the free ends thereof normally disengaged, and cam means on one of said contact spring units continuously engaged by an extending portion of said armature and adapted to effect engagement and disengagement of said contacts upon rocking movement of said armature, each of said units being separately removable from said base member independently of the other units.
